UNITED STATES PATENT OFFICE.

RAGNVALD ECK, OF CHICAGO, ILLINOIS, ASSIGNOR OF ONE-HALF TO WILLIAM P. CROCKETT, OF CHICAGO, ILLINOIS, AND ONE-HALF TO THE ECK TOOL COMPANY, OF CHICAGO, ILLINOIS, A CORPORATION OF ILLINOIS.

PIPE-CUTTER.

1,003,442.

Specification of Letters Patent. Patented Sept. 19, 1911.

Application filed April 13, 1908. Serial No. 426,655.

To all whom it may concern:

Be it known that I, RAGNVALD ECK, a citizen of the United States, residing at Chicago, county of Cook, and State of Illinois, 5 have invented certain new and useful Improvements in Pipe-Cutters, of which the following is a description.

My invention relates to means for cutting metallic pipe at substantially right-angles 10 to its axis and particularly to a conveniently portable size of device adapted for this purpose.

The object of my invention is to provide a simple, compact, light and durable device 15 of the kind described, adapted to sever the end of the pipe without raising a bur or fins either upon the inside or outside of the pipe.

To this end my invention consists in the novel construction, arrangement, and combination of parts herein shown and described, and more particularly pointed out 20 in the claims.

In the accompanying drawings wherein like or similar reference characters indicate 25 like or corresponding parts; Figure 1 is a front elevation of my device. Fig. 2 is a side elevation of the same. Fig. 3 is a section taken substantially on line 3—3 of Fig. 1. Fig. 4 is a section taken substantially 30 on line 4—4 of Fig. 1. Fig. 5 is a section taken substantially on line 5—5 of Fig. 3. Fig. 6 is a section taken substantially on line 6—6 of Fig. 3. Fig. 7 is an enlarged sectional detail of the cutter employed in my 35 device. Fig. 8 is a section similar to that shown in Fig. 7 but showing a slightly modified form of the cutter.

In the preferred construction shown in the drawings, my device consists of a suitably formed frame provided with a lateral projection at each end, a guide or way extending between the projections, and a slide mounted upon said guide. The projection at one end of the frame is suitably formed 40 to engage a pipe or other cylindrical body and hold the frame at substantially right angles to its axis. The projection at the opposite end of the frame is provided with a screw or other suitable means adapted

to engage the slide and control its position 50 upon the guide.

As shown the frame consists of two substantially parallel cylindrical rods 1—1 rigidly connected at their extremities by suitably formed members 2 and 3 respectively. The member 2 may be of any suitable form adapted to engage a pipe or other cylindrical object and hold the frame at substantially right angles to the axis of the object while permitting the free movement of the frame about the object. In the form shown the member 2 extends laterally from the members 1 and is provided with a recess 4 in its face of suitable form to receive a pair of rollers 5 and support the 60 frame substantially parallel to the common plane of the rods 1—1. The rollers 5—5 may be of any suitable form. As shown each roller is substantially cylindrical and of sufficient length to hold the frame at 70 substantially right angles to the axis of a pipe or similar object against the surface of which the rollers are securely held. Each roller is preferably mounted upon a suitable pin or shaft 6 the ends of which are rigidly 75 supported in the walls of the recess 4 the rollers each being preferably freely rotatable upon their respective pins 6.

The connecting part 3 also projects laterally and is provided with an opening 7 substantially parallel to the rods 1. The lateral distance from the center of the opening 7 to the rods 1 preferably corresponds to the distance from the rods 1 to a point intermediate the rollers 5—5. In the 85 preferred construction a portion of the opening 7 is threaded and a rod 8 or other suitable means provided with a threaded portion at one end adapted to cooperate with the threads in the opening 7 is positioned in the opening. A handle 9 or equivalent means is preferably provided at the outer end of the rod 8 to rotate the same to control its position in the opening.

The parts 2 and 3 may be attached to the 95 rods 1—1 in any suitable manner. In the form shown a portion 10 of each rod 1 is reduced in diameter to form a concentric

shoulder 11 near the ends of the rod and the outer end of the reduced portion is threaded and provided with a suitable nut. The members 2 and 3 are each provided 5 with suitable openings extending longitudinally therethrough with a part of each opening adapted to fit the body of the rod and a part adapted to fit the part 10 with a shoulder within the opening to engage 10 the shoulder 11 and positively control the position of the parts upon the rods. This construction provides a strong and satisfactory connection between the rods and the parts 2 and 3 and gives the full strength 15 of the rods 1 to resist the bending tendency produced by the outward pressure upon the lateral projections of the parts 2 and 3.

Any desired form of longitudinally movable member may be provided upon the rods 20 1 to carry the cutting disk of my device. In the form shown a slide 12 is provided for this purpose having portions extended at each side and provided with openings 14—14 adapted to receive the rods 1—1 to accurately 25 control the position of the slide in relation to the parts 2 and 3. A suitable recess 19 is provided in the face of the slide adjacent the part 2 to receive the cutter 15. A boss 16 is provided with a recess or opening 30 17 extending longitudinally of the guides 1—1 to receive the end of the rod 8 to control the position of the slide upon the guides.

The rod 8 may be attached to the slide 12 35 in any suitable manner. In the form shown the rod 8 is reduced and provided with a concentric groove 17' near its end. A pin 18 or other suitable means is positioned in a suitable opening in the boss 16 40 so positioned that the pin will engage the groove 17' and thus rotatably connect the rod 8 and slide 12.

Any suitable form of cutting disk may 45 be employed. As shown, a suitable hub 20 is provided upon each side of the disk thus providing an extremely long bearing for the cutter upon its shaft 23 and avoiding any tendency of the disk to cramp upon its shaft when in operation. The hubs 20 are 50 so proportioned as to bring the cutting edge of the disk substantially midway between the ends of the rollers 5. The ends of the hubs engage the walls of the recess 19 to control the transverse position of the cutting 55 edge of the disk. In the preferred construction the periphery of the cutter 15 is provided with one face inclined to the axis of the cutter as at 21 and the opposite side 22 substantially perpendicular to the axis, the 60 two sides meeting near the periphery of the perpendicular side of the cutter to form the cutting edge. The perpendicular side is preferably slightly beveled at its periphery so that while the cutting edge is very near

the perpendicular face of the cutter it is 65 preferably not located exactly in its plane. The object of this slight beveled portion is to avoid any tendency of the cutting edge of the cutter to crumble away in use and also it is found in practice that it materially aids 70 in starting the operation of the device, and tends to avoid any tendency of the cutter to travel along the pipe as the tool is rotated about the same. In the preferred construction also the shaft 23 upon which the cutter is mounted is inclined slightly from the common plane of the rods 1—1, the preferred arrangement being that the hub 20 adjacent the perpendicular side 22 of the cutter is slightly farther from the common plane of 80 the rods 1—1 than the opposite hub so that the cutter when positioned is at a slight angle to the axis of the pipe upon which it is operating, tending to relieve any crowding, or the tendency to move the cutter longitudinally of the pipe and also relieve the pressure upon the flat side of the cutter after the pipe is partially severed. This arrangement also tends to materially assist in mounting the cutter upon the work and 90 greatly increases the life of the cutter.

In operation my device is placed upon the pipe in the usual manner and the cutter 15 brought into contact with the surface of the pipe after which the cutter is rotated about 95 the pipe in the direction indicated in Figs. 1 and 3, thus forming a shallow groove entirely around the pipe after which the handle 9 is operated to force the cutter with any desired pressure against the side of the 100 pipe. The cutter is then rotated as before to sever the pipe in substantially the usual manner, the pipe being severed with one substantially square face and one beveled face. The square face is substantially free 105 from burs or projections both on its exterior and interior, thus eliminating the necessity of reaming or filing or any other operation commonly necessary with the usual forms of pipe cutters where it is desired 110 to secure the full area of the pipe opening at the extremities. The work in all respects produced by my cutter is substantially the same as where the pipes are cut upon an engine lathe or similar devices.

The severed portion having the beveled face above referred to is not appreciably different from that produced by the ordinary form of cutter, that is, there is usually a slight intruded bur or flange but where 120 this is objectionable my device may be merely reversed and so positioned as to cut off the beveled portion of the pipe with very little or no waste thus providing a flat end as above described.

Having thus described my improvement, it is obvious that various immaterial modifications may be made in my device without

departing from the spirit of my invention, hence I do not wish to be understood as limiting myself to the exact form and construction shown.

5 What I claim as new, and desire to secure by Letters Patent is:

1. In a pipe cutter, a frame comprising a plurality of substantially parallel rods rigidly connected at their ends, a projection at 10 one end of said rods to engage the work and hold the frame at right angles thereto, a member mounted upon said rods for movement longitudinally thereof and carrying a single rotatable cutting disk with the axis of 15 said disk slightly inclined to the common plane of the rods and to the axis of the work, and means for controlling the position of said member upon the rods.

2. In a pipe cutter, a frame comprising a 20 plurality of substantially parallel rods rigidly connected at their ends, a projection at one end of the rods to engage the work and hold the frame at right angles thereto, a member mounted for longitudinal movement 25 on the rods and carrying a rotatable disk having one face inclined and the other perpendicular to its axis whereby the cutting edge of said disk is formed substantially at said perpendicular side, and said disk carrying 30 member supporting the disk with the axis of the disk slightly inclined to the common plane of the rods, and to the axis of the work to be operated upon, and means for controlling the position of the disk-carrying 35 member upon said rods.

3. In a pipe cutter, a frame comprising a plurality of substantially parallel rods rigidly connected at their ends, the connection at one end of the rods being extended laterally and arranged to engage a cylindrical object to hold said frame at substantially right angles thereto, a member mounted on the rods for longitudinal movement and carrying a single rotatable disk having one face 45 thereof inclined and the other perpendicular to its axis, whereby the cutting edge of said disk is formed substantially at said perpendicular side, said disk-carrying member supporting the disk with the axis of the disk 50 slightly inclined to the common plane of the rods and to the axis of the cylindrical work to be operated upon, and means for controlling the position of said member upon the rods.

55 4. In a pipe cutter, a frame comprising a plurality of substantially parallel rods rigidly connected at their ends, the connection at one end of said rods being extended laterally and arranged to engage cylindrical 60 work and hold the same at substantially right angles thereto, a member mounted for longitudinal movement upon the rods and provided with a single rotatable cutting disk having one face inclined and the other

perpendicular to its axis, whereby the cutting edge of said disk is formed substantially at said perpendicular side, said disk-carrying member supporting the disk with the axis of the disk slightly inclined to the common plane of the rods and to the axis 65 of the work to be operated upon, the connection at the other end of said rods being also extended laterally and provided with a threaded bore extending therethrough, and a screw-threaded rod arranged to engage 70 the threaded bore of said last mentioned lateral extension and connected with the disk carrying member to control the position of said member upon said rods.

5. In a pipe cutter, a rotatable cutting 80 disk having one face inclined, and the other perpendicular, to the axis of the disk, the perpendicular face being beveled slightly at its periphery to meet said inclined face, thereby forming the cutting edge of said 85 disk in close proximity to said perpendicular side.

6. In a pipe cutter, a rotatable cutting disk having one face inclined and the other perpendicular to the axis of the disk, the 90 perpendicular face being beveled slightly at its periphery to meet said inclined face, thereby forming the cutting edge of said disk in close proximity to said perpendicular side, a frame for rotatably engaging a 95 pipe and holding said disk with the axis thereof at a slight inclination to the axis of the pipe.

7. A pipe severing implement constructed and arranged to be moved circumferentially 100 of the work but to be held stationary with respect to movement longitudinally thereof during the cutting operation and comprising a frame including means at one end thereof to engage the work and hold the 105 frame at right angles thereto, and a rotatable cutting disk supported on the frame with its axis slightly inclined to the longitudinal axis of the frame and to the axis of the work to be operated upon.

8. A pipe severing implement constructed and arranged to be moved circumferentially 110 of the work but to be held stationary with respect to movement longitudinally thereof during the cutting operation and comprising a frame including means at one end thereof to engage the work and hold the frame at right angles thereto, and a cutting disk supported on the frame with its axis slightly inclined transversely to the longitudinal axis of the frame and also inclined to the axis of the work to be operated upon.

9. A pipe cutter comprising a frame including a guide and a lateral projection at one end of the guide to engage the work 115 and hold the guide at right angles to the same, a cutter carrying member arranged for movement longitudinally of the guide,

a rotatable cutting disk carried by said member with the axis of the disk inclined transversely to the longitudinal axis of the guide and to the axis of the work to be held by the lateral projection, said cutting disk having one face inclined and the other perpendicular to the axis of the disk, the perpendicular face being beveled slightly at its periphery to meet said inclined face, thereby forming the cutting edge of said disk in

close proximity to said perpendicular side, and means for controlling the position of the cutter-carrying member on the guide.

In testimony whereof, I have hereunto signed my name in the presence of two subscribing witnesses.

RAGNVALD ECK.
